FIG. 1

FIG. 2

FIG. 3

FIG. 1 is a front perspective view of a table lamp, showing my new design;

FIG. 2 is a rear elevational view thereof as shown in FIG. 1;

FIG. 3 is a side elevational view thereof as shown in FIGS. 1 and 2, the lamp shade having been removed;

FIG. 4 is a top plan view thereof as shown in FIGS. 1 and 2; and

FIG. 5 is an enlarged sectional view taken substantially along line 5-5 of FIG. 3.

The dominant features of my design reside in the portions shown in full lines.

I claim:

The ornamental design for a table lamp, as shown and described.
